UNITED STATES PATENT OFFICE.

WILLIAM TOENNES, OF HAZLETON, PENNSYLVANIA.

INSTALLMENT-PAY ENVELOP.

1,283,975.

Specification of Letters Patent.

Patented Nov. 5, 1918.

Application filed March 12, 1918. Serial No. 221,882.

To all whom it may concern:

Be it known that I, WILLIAM TOENNES, a citizen of the United States, residing at Hazleton, in the county of Luzerne and State of Pennsylvania, have invented certain new and useful Improvements in Installment-Pay Envelops, of which the following is a specification.

My invention is particularly adapted for use by the members of churches, lodges, and societies where such members pay a certain amount of money periodically. Prior to my invention the persons, such as above noted, were usually given a pack or number of envelopes, each envelop being dated for the particular day upon which the payment fell due; for example, in a church the member who had pledged a certain sum to the church, to be paid in weekly installments, was given a number of envelopes dated consecutively, one envelop for each Sunday in the year. These envelopes were usually deposited in the collection plate and after the money was removed the envelop, having no further use, was destroyed. Envelops of the above mentioned type are expensive and since they are only used once, it is necessary to supply new envelopes after they have been once used in order to allow a person to continue periodic payments.

The main object of my invention is to do away with this waste of material by providing a series of envelopes which, for example, a church member can successively use to make installment payments and after the last envelop of the series has been used the entire series can be returned to said member and used over and over again in the same manner, each of the envelopes being provided with a certain arrangement of dates which keep the member posted as to which envelop to use in repeated succession of the series.

Another object of my invention is to provide the back of each of the envelopes with a constant number and other inscription opposite which a person can designate the purpose for which the inclosed money is to be applied.

These objects, and other advantageous ends which will be described hereinafter, I attain in the following manner, reference being had to the accompanying drawings in which

Figure 1 represents the front face view of

the first of a series of envelops made in accordance with my invention.

Fig. 2 is the rear face view of the envelop shown in Fig. 1.

Fig. 3 is a longitudinal section of the envelop, and

Figs. 4 to 28, inclusive, represent front face views, of similar character to Fig. 1, and illustrate the numerical order in which the envelops can be consecutively used for a period of six months and then reused every six months, considering that the payments are made every Sunday, beginning January 5, 1919.

Each envelop of the series is inscribed on its front face with a plurality of dates and these dates are indicative of the periods in which payment is to be made in that particular envelop. It will be noted that each of the series of envelops illustrated in the drawings is adapted to be used once every six months so that in making weekly payments the series illustrated would last six months, beginning with January 5, 1919, as illustrated in Fig. 1, and ending June 29, 1919, as illustrated in Fig. 28, there being twenty-six envelops in this series.

To continue the use of these envelops throughout the year 1919, the envelop shown in Fig. 1 would be again used on July 6, following the use of the envelop illustrated in Fig. 28 on June 29, 1919, and the successive use of the envelops in the order illustrated, repeated until on December 28, 1919, the envelop shown in Fig. 28 would be again used. Beginning with the year 1920, the envelop shown in Fig. 1 would be first used on January 4, the envelop shown in Fig. 4 would be the second used on January 11, the envelop shown in Fig. 5 would be the third used on January 18, and so on until the series is entirely used. As illustrated, the series of envelops would last, for weekly payments, throughout a period of ten years.

As shown in the accompanying drawings, the front face of each of the envelops is divided into a number of columns 1, 2, 3, 4, 5, and 6 by vertical lines 7 which can be printed thereon. Each of the columns is subdivided by lines 8 which produce the rectangular spaces, as illustrated, and provides the spaces in which the dates of the month and year are inscribed by printing or otherwise. The spaces included in the

columns 1 and 4 have the years inscribed therein and the monthly dates in which the envelop is to be used in the different years are arranged opposite the years and within 5 the columns 2, 3, 5, and 6; for example, in Fig. 1 the space 9 has "Jan. 5" inscribed therein directly to the right of the year 1919. The space 10, which is in alinement with the year 1919 and also in alinement 10 with the date Jan. 5, indicates that this envelop is to be used again on July 6, 1919. In this manner persons can easily keep account of their installment payments.

The envelops can be made of tough paper, 15 "fibroid", or the like, and a tab 11 can be provided and secured in place by an ordinary clip or any means desired, just so that it is not pasted. The back face 12 of the envelop is preferably provided with a line 20 13 for the name of the person making the payments and also with a number which is similar on the back of each of the envelops of the series. The back face of each of the envelops can be provided with other inscription, 25 such for example as illustrated in Fig. 2.

While I have described my invention as taking a particular form, it will be understood that the various parts of my invention 30 may be changed without departing from the spirit thereof, and hence I do not limit myself to the precise construction set forth, but consider that I am at liberty to make such changes and alterations as fairly come 35 within the scope of the appended claims.

Having thus described my invention, what I claim as new and desire to secure by Letters Patent is:

1. A series of installment pay envelops

adapted to be repeatedly used in successive 40 order, each of the envelops of said series having an actual date thereon in regular succession, in the order of use, to an actual date on the envelop immediately preceding it in said order of use, substantially as described. 45

2. A series of installment pay envelops adapted to be repeatedly used in successive order, each of the envelops of said series having a plurality of actual dates thereon in 50 regular succession, in the order of use, to actual dates on the envelop immediately preceding it in said order of use, substantially as described.

3. A series of installment pay envelops 55 adapted to be repeatedly used in successive order, each envelop of the series having inscribed thereon a plurality of different actual dates, each of the envelops among said dates including dates which occur between 60 successively inscribed dates on other of said envelops, substantially as described.

4. A series of installment pay envelops having a succession of actual year dates inscribed thereon; and a plurality of monthly 65 dates inscribed on said envelops after each of the years and being different on each envelop, certain of the month dates on each envelop being those which occur between 70 successive monthly dates on others of the envelops, substantially as described.

In testimony whereof I have signed my name to this specification in the presence of two subscribing witnesses.

WILLIAM TOENNES.

Witnesses:

MARY A. INGLAR,
CHAS. E. POTTS.
